Patented July 24, 1917.

UNITED STATES PATENT OFFICE.

FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

ELECTRIC UNIT.

1,234,149.

Specification of Letters Patent. Patented July 24, 1917.

Application filed March 27, 1917. Serial No. 157,732.

To all whom it may concern:

Be it known that I, FREDERICK M. FURBER, a citizen of the United States, residing at Revere, in the county of Suffolk and State of Massachusetts, have invented certain Improvements in Electric Units, of which the following description, in connection with the accompanying drawings, is a specification, like reference characters on the drawings indicating like parts in the several figures.

This invention relates to electric heating units of general utility.

Heretofore when electric units have been used in situations where they are subjected to severe shocks or vibrations it has been found that they deteriorate rapidly and that the repeated stress to which they are thus subjected leads to their destruction in a short time.

Great difficulty has been experienced by reason of the breaking of the resistance wire where its ends are fastened. This wire is often very small, and in units as heretofore constructed, has been fastened at its ends in a manner involving some form of more or less sharp bend. This, of course, puts one side of the wire in tension and the other side under compression, and when such units are used in situations where they are subject to rapidly recurring shocks, which, in themselves, as is well known, tend strongly to produce disorganization of molecular arrangement, the non-homogeneity of intermolecular stress at the bend produced by the sharp curvature there causes the wire to yield rapidly to this disorganizing tendency, with the result that it soon breaks.

Another cause of damage at this point is corrosion at the junction of the resistance wire and the terminal member to which it is fastened. The cause of this corrosion is somewhat obscure, but may be connected with thermo-electric effects due to the heating of the junction of two dissimilar metals.

Resistance wire is selected solely with regard to its qualities as a durable resistance, and its composition is therefore determined largely without regard to any possible relation it may have to other parts of the unit. Terminal members have been heretofore selected with regard to mechanical considerations alone. I have found that by properly selecting the material of which the terminal member is made, with regard to

the material of which the resistance wire is constructed, (or vice versa), the corrosion of the parts at the junction of the wire and terminal members, and consequently the destruction of the unit, can be avoided.

60

The unit shown in the accompanying drawings is designed particularly for use in shoe machinery, where the space for it is extremely limited, and where it is subjected to swiftly recurring jars and shocks. The limitation as to space enforces the use of 65 very small wire, less than 0.01 inch in diameter, and the violent treatment which the unit undergoes makes imperative the preservation of the wire from any corrosion, since 70 a very small degree of deterioration will destroy it.

I have found that corrosion at the junction of the wire and terminal block can be obviated by avoiding too great a chemical 75 dissimilarity in the elements composing the joint. I conceive that the presence in these elements of elements belonging to the same chemical group has a favorable effect on the corrosion phenomena. In the unit shown 80 in the drawings the resistance wire is the well-known nichrome wire, and the terminal member is of nickel steel. I have found that the junction of this combination of materials is entirely free from corrosion.

85

A feature of my invention is accordingly an electric unit having resistance wire and a terminal member each having an element belonging to the same chemical group in its composition. In the unit described this 90 group is the iron group, and the specific elements are iron and nickel.

This and other features of the invention will be understood from the following description of a preferred embodiment of the 95 invention, selected for purposes of illustration and shown in the accompanying drawings, in which;

Figure 1 is a section of the head of a burnishing machine showing the unit in 100 elevation;

Fig. 2 is an enlarged elevation of the unit partly in section on the line 2—2 of Fig. 1; and

Figs. 3, 4 and 5 are details showing the 105 manner of fastening the ends of the resistance wire.

The shaft 10 is oscillated rapidly in suitable bearings not shown. It carries the head 11 upon which is mounted the tool carrier 110

12, which supports the burnishing tools 13. The tool carrier 12 has a bore 14 in which is mounted the unit and which has a mica floor 14'. Slots 15 in the walls of the upper 5 end of the bore 14 permit the egress of the lead wires.

The unit is built up on a nickel steel rod 16, having a head 17 at one end. To this head is brazed one of the flexible lead wires 18, which carries a lava bead 19, a number 10 of glass beads 20 and the terminal 21. The lava bead 19 rests in the slot 15 and resists, better than a glass bead, the intense heat at this point.

15 Next to the head 17 on the rod 16, is mounted a mica washer 22, which is of larger diameter than the head 17, and just fits the bore 14. Next to the mica washer 22 is mounted a lava ring 23, around which is 20 placed the nickel steel terminal ring 24, to which the other flexible lead wire 25 is brazed. The rings 23, 24 are of the same width, and the diameter of the ring 24 is less than that of the washer 22. Next on 25 the rod 16 is located the lava core 25', which is of the same diameter as the terminal ring 24 and is helically threaded throughout its length. Next to the core is mounted in electrical contact with the rod 16, a nickel steel 30 terminal 26 of the same diameter as the core, and next to the terminal 26 is mounted another mica washer 27, identical with the washer 22. Below this is mounted a steel washer 28 upon which the rod 16 is upset 35 at 29.

The resistance wire 30 is wound in the helical thread, and fastened to its terminal elements 24, 26 in the manner shown in Figs. 3, 4 and 5. A slot 31 is cut in each 40 of the elements 24, 26, the ends of the wire 30 are placed in the slots, and each of the lips 32 is then upset over the wire by a punch stroke, clamping it firmly in position.

45 Of the numerous kinds of resistance wire obtainable on the market, I have found the Driver-Harris Wire Company's nichrome wire the most satisfactory. This wire contains 50% or more of nickel and a smaller percentage of chromium. Though the performance and durability of this wire as a resistance were found adequate, and the terminal fastening means prevented mechanical destruction at the joint, considerable difficulty was at first experienced with corrosion 50 at this point, the terminal rings 24 and 26 being of copper in the first units made. I found that by replacing the copper with a material having a closer relation to the wire in regard to chemical composition, the corrosion 55 difficulty could be avoided. A convenient material for this purpose was found to be nickel steel, no appreciable corrosion appearing in the units in which it was used for terminals. I regard this freedom from 60 corrosion as due to the presence of chemi-

cally related elements in the materials which form the joint. Iron and nickel both belong to the same chemical "family" or "group" and there is accordingly a substantial amount of material belonging to the same 70 chemical group in both of the joint forming members.

The current flows through the wire 18, head 17, rod 16, terminal 26, wire 30, ring 24, to the wire 25. The washers 22, 27 75 project beyond the outer cylindrical portions of the unit, and insulate it from the wall of the bore 14. The floor 14' insulates the end of the rod 16. The necessity of a cover or case for the unit is thereby avoided, 80 and the heat is more easily and directly conveyed to the tools.

The lava used in the core 25' has a mean thermal coefficient of expansion between 70° F. and 935° F., (just visible red) of 85 0.000,0070 per 1° F., which is substantially that of steel. The nickel steel rod 16 used in the unit described has a mean thermal coefficient of expansion between the same limits of 0.000,0076 per 1° F. The relative coefficient of expansion between these limits per 1° F., is, therefore, 0.000,0006. The unit itself is about 2½ inches long. The relative expansion of the steel rod and lava core in this unit when heated from 70° F. 90 to 930° F. would be, therefore, $(930-70) \times 2\frac{1}{2} \times 0.000,0006 = 0.0012$ inch.

The rod 16 is so upset as firmly to compress the other elements of the unit between its ends. The mica washers 22, 27 are more 100 compressible than the other elements mounted on the rod 16, and will safely take stresses due to the heading up of the rod 16, which might crush a more unyielding structure. At the same time the washers are sufficiently elastic to take up the relative expansion, necessarily minute, as shown, of the nickel steel rod 16 and the lava core 25', when heated in use. The materials of the unit supported on the rod 16 are thus bonded 110 together in a compact mass, always under a substantial compression. I have found that the lava core is very resistant to shocks and that when it does break, it breaks crosswise and not lengthwise. The longitudinal 115 compression exerted by the rod 16 upon the core effectively precludes danger of breakage of this sort.

The means adopted for fastening the ends of the resistance wire avoids the heretofore experienced breakage of the wire at these points. The slot 31 is substantially in the prolongation of the helix in which the wire is wound on the unit, and the wire enters it without substantial bending. The upsetting 120 of the sides of the slot on the wire applies a pressure to the wire which is substantially uniform circumferentially and progressively increases from zero to a maximum longitudinally, from the ends of the slot to its 125

middle so that sharp variations in molecular stress are avoided. It will be seen that in the unit shown, all the resistance wire is open to inspection and manipulation and 5 that a burned out wire can be readily replaced by the operator, by merely spreading the slots 31 and upsetting them again.

I do not claim broadly the use of nickel in a terminal member herein, as I have 10 claimed it in my co-pending application Serial No. 36,721, filed June 28, 1915.

Having described the invention, what I claim as new and desire to secure by Letters Patent of the United States is:

15 1. An electric unit having resistance wire, and a terminal member to which it is fastened, the wire and member each containing a substantial quantity of material belonging to the same chemical group.

20 2. An electric unit having resistance wire, and a terminal member to which it is fas-

tened, the wire and member each containing a substantial quantity of material belonging to the iron group.

3. An electric unit having resistance wire 25 and a terminal member to which it is fastened, the wire and member containing substantial amounts respectively, of different materials belonging to the same chemical group.

30 4. An electric unit having resistance wire with nickel in its composition, and a terminal member for said wire having nickel in its composition.

5. An electric unit having resistance wire 35 with nickel and chromium in its composition, and a terminal member of nickel steel for said wire.

In testimony whereof I have signed my name to this specification.

FREDERICK M. FURBER.
